(57) **CLAIM**

The ornamental design for a reflecting mirror, as shown and described.

DESCRIPTION

FIG. 1 is a top, rear, left perspective view of a reflecting mirror, showing our new design.

FIG. 2 is a rear elevation view thereof;

FIG. 3 a front elevation view thereof;

FIG. 4 is a right side elevation view thereof;

FIG. 5 is left side elevation view thereof;

FIG. 6 is top plan view thereof; and,

FIG. 7 is a bottom plan view thereof.

The broken lines of uneven length in FIGS. 3 and 7 illustrate the boundary of a portion of the reflecting mirror that forms no part of the claimed design.

1 Claim, 7 Drawing Sheets
